DESIGN FOR A TEXTILE FABRIC

Philip F. Rothmann, Brooklyn, N. Y.

Application June 6, 1935, Serial No. 57,176

Term of patent 3½ years

To all whom it may concern:

Be it known that I, Philip F. Rothmann, a citizen of the United States, residing at 115 Logan Street, in the Borough of Brooklyn, county of Kings, city and State of New York, have invented a new, original, and ornamental Design for a Textile Fabric, of which the following is a specification, reference being had to the accompanying drawing constituting a part hereof.

The design is characterized by a pattern having woof threads skipping warp threads forming the corners of a square, the body of the fabric having warp and woof threads interlaced.

The figure is a plan view of a piece of textile fabric showing my new design.

I claim:

The ornamental design for a textile fabric substantially as shown and described.

In testimony whereof, I have hereunto subscribed my name this 29th day of May, 1935.

PHILIP F. ROTHMANN.
